SNAP SWITCH MECHANISM

Mark N. Russell and William F. Zimmerman,
Syracuse, N. Y., assignors to Pass & Seymour,
Inc., Syracuse, N. Y., a corporation of New York

Application March 1, 1948, Serial No. 12,216

16 Claims. (Cl. 200—67)

1

This invention relates to electric circuit makers and breakers and more particularly to what are commonly known as snap switches of the type used principally for the control of lighting circuits in residences, stores, offices, factories and the like.

It is a general object of the present invention to provide a novel type of snap switch and a unique principle of operation for such switches.

More particularly it is an object of the present invention to develop a switch of the snap type based on the engagement between a rigid oscillatable member and a resilient prestressed contact in such a manner that rebound is substantially prevented.

An important object of the present invention consists in arranging the resilient contact unit so that it is preloaded and capable of rapidly transferring the preload to the rigid contacting member without changing the stress pattern in the preloaded portion thereof whereby rebound and consequent arcing of the contacts is prevented.

Another object of the invention consists in the construction and arrangement of the resilient contact unit and the switch casing whereby the assembly thereof automatically applies preload to a designated portion of the unit.

Still another object of the present invention consists in the construction and arrangement of an integral stationary contact unit for snap switches from resilient sheet metal of spring hardness to comprise a relatively large terminal area, a rigid foot or blade portion and an elongated intermediate or connecting section which is adapted to be torsionally stressed at all times by suitable deflection of said foot and in which the intermediate and blade portions are formed to remain in the plane of the original metal stock until assembled into the switch.

A further object of the present invention consists in the construction and arrangement of an integral molded casing for a snap switch of the type described in which recesses are provided to receive and immobilize the terminal portion of the stationary contact unit and to fulcrum the heel of the blade thereof and in which an inclined abutment engages the blade beyond the heel and deflects it about the fulcrum as the contact unit is moved into position into said recesses and applies torsional preload to the section of the unit between the terminal and blade portions.

One of the features of the snap switch of the present invention is the arrangement of the casing thereof with slots and recesses to receive a

2

stationary contact unit and position it without the use of fastening means other than the casing cover, and with surfaces cooperating with the unit during and after insertion to preload the unit in such a manner that the preload is transferred to an engaging contact without changing the flexure pattern in the stationary contact.

Another feature involving the elimination of contact rebound on circuit closing is based on the torsional stress imparted to a flat spring-like connecting portion of the contact unit extending between an immobilized terminal portion and a laterally projecting rigid blade by its engagement with portions of the casing so arranged that the moving contact can quickly assume this preload and increase the torsion in said connecting portion without changing the stress pattern therein.

Other and further objects and features of the invention, including constructional arrangements and cooperation of the various parts thereof will be more apparent to those skilled in the art upon a consideration of the accompanying drawings and following specification wherein is disclosed but a single embodiment of the invention, with the understanding that such modifications may be made therein as fall within the scope of the appended claims.

In said drawings:

Fig. 1 is a longitudinal central section on an enlarged scale through a single pole switch constructed according to the present invention and with the parts arranged in the "off" position;

Fig. 2 is a fragmentary top plan view of the switch casing and assembled stationary contact units and their terminals;

Fig. 3 is a sectional view taken parallel to the top and bottom faces of the casing in the plane of line 3—3 of Fig. 1 and showing the amount of preflexure of the stationary contacts as effected by assembling them in the housing;

Fig. 4 is a transverse section taken on the plane of line 4—4 of Fig. 1, showing only a single stationary contact in position;

Fig. 5 is a fragmentary view similar to Fig. 3 but showing the bridging contact engaging the stationary contacts;

Fig. 6 is a top plan view of the stationary contacts in relaxed position;

Fig. 7 is a side elevation of the contact of Fig. 6; and

Fig. 8 is a front elevation thereof viewed in the plane of the blade and connecting portion.

Snap switches of the type commonly recessed in walls and used principally for the control of illumination in residences, offices, stores and the

like, operate under the serious handicaps of small size, easy operation, low cost, heavy loads and lamp-load surges. Type C Mazda lamps prevail in most installations and are particularly troublesome because of their characteristic rapid current rise to a peak of approximately ten times that of the steady-state value when the circuit is first closed. This is also the interval when contact vibration occurs in most switches and results in arcing and burning which rapidly destroys the contacts.

10 Snap switches operate by engaging one or more substantially stationary contacts by a spring snapped movable contact. They have been constructed in many ways to endeavor to eliminate the above difficulties. In the blade type of switch preloading of the movable contacts was a satisfactory solution of the problem, as taught by Patent 2,318,015, granted May 4, 1943, to Russell and Keilien.

In the more popular type of snap switch in which laterally spaced stationary contacts are bridged by the rigid snap member or by a contact thereon unsuccessful attempts have been made to apply preloading, but vibration was not damped properly since by their construction the stationary contacts were stressed by bending and the impact from the bridging member of necessity occurred at some distance from the point of application of the preload and hence the bridging member did not immediately assume the preload and vibration occurred.

The switch of the present invention is of the popular snap-yoke-bridging type arranged for wall box mounting by means of a top strap 10, seen in Fig. 1, which serves also to retain the insulation cover 12 over the open upper or front face of the switch casing 14 which is of unitary molded construction closed at bottom, ends and sides.

A U-shaped yoke 15 has trunnions journaled in notches 16 in the side walls 17 of the casing beneath the notches 18 forming journals for the integral trunnions 19 on the molded handle unit 20.

This handle unit includes depending post 21 having a hemispherical end providing a sliding fit with the smaller diameter top turn of helical spring 22. The post and spring pass between the arms of the yoke, and the reduced lower end of the spring fits seat 23 integral with the lower yoke portion. This construction provides snap action to throw the yoke from the position shown in Fig. 1 against stop 24 to the corresponding opposite position against stop 25. Lateral shoulders 27 on the handle unit engage beneath the insulating cover 12 and form limiting stops for the handle, the manipulative portion of which extends out through a slot 28 in the insulating cover and in the strap. To insure positive kick-off of the yoke in the event it should not be immediately loosened by the spring, the lower extensions 30 of the shoulders 27 are arranged to engage the upper ends of the yoke arms at 31 above the axis of the trunnions.

The invention is independent of the construction and operation of the snap mechanism and deals principally with the construction and arrangement of the relatively stationary contacts, two of which are illustrated in Fig. 2 positioned to be bridged by the cross member of the yoke 15, which is of conducting metal and rigid enough to resist vibration at frequencies which might be imparted to it by the snap mechanism, by sud-

den engagement with the stationary contacts, or with either of the yoke stops 24 and 25.

Figs. 2, 3 and 5 show the switch provided, in the single-pole type, with a pair of relatively stationary contact units 32 and 34, spaced apart transversely near one end of the housing and symmetrically and oppositely disposed. Their blade portions, which shall be more fully described later, bear, intermediate their lengths, on the vertical edges of the yoke stop 25 and their forward flared ends extend beyond it toward the center of the casing to receive between them the transverse member of the yoke. Fig. 5 illustrates this rigid yoke element 15 engaged between the blades of the stationary contacts and resting also against the stop 25, which is closed circuit position of the switch.

The contact units as briefly referred to are integral stampings formed from flat sheet metal such as bronze of spring hardness. They are formed to the shape illustrated in Figs. 6, 7 and 8, with those on opposite sides of the yoke stop of opposite hand. Referring now to the three figures mentioned, it will be seen that each contact unit includes a relatively large, substantially square, flat area 35 having an upwardly open slot 35' therein for a purpose which shall be subsequently defined.

Extending at substantially a right angle to the plane of area 35 and from the mid portion of the lower edge thereof is offset section 36, the side edges of which extend at substantially right angles to the plane of 35. Depending from the remote edge of the offset portion and at substantially a right angle thereto is connecting section 37 merged with the remote edge by means of a flange 38. This remote edge is not parallel to the junction of 35 and 36 but extends at a small angle thereto, as clearly seen in Fig. 6, whereby the parts 35 and 37 are not in parallel planes although the vertical axes of the two planes are parallel. The flange 38 and the connecting portion 37 are arranged to merge with a slight extension 39 in the offset portion whereby a rigid corner is formed at 40 to prevent twisting of the junction of 36 and 37. The right hand edge of 37, as viewed in Fig. 7, is not substantially out of alignment with the corresponding edge of the terminal area 35.

The part 37 is relatively narrow and of substantially uniform width. Springing from its left edge near and at the lower end thereof is the transverse blade 41 widened in a vertical direction at 42 to provide adequate contacting area remote from the connecting portion and having a canted or flared tip 44 providing for entrance of the yoke between the two blades with effective guidance. The line 45 of junction between the blade 41 and the canted tip is at such an angle as will be formed by the plane of the yoke when passing between the tips. From the junction of the line 45 with its bottom edge substantially to the heel 46 of the blade and connecting portion, there extends flange 47 at right angles to the plane of the blade and substantially parallel to the offset portion 36. In plan this flange, as shown in dotted lines in Fig. 6, is of substantially uniform width with rounded corners.

The contact unit will be seen to provide a flat area which can be immobilized in the casing, an offset portion to position the connecting portion away from the wall of the casing, and a blade or foot extending from the connecting portion and having a heel, unencumbered by the flange which provides stiffness for the remainder of the blade

to substantially prevent bending of the same under any lateral stress imparted to it. The unencumbered heel fits in a slot in the wall of the casing, which acts as a fulcrum so that when contact loading is effected by displacing the blade by lateral pressure on its inner face a substantially pure torsional stress is imparted to the connecting or spring portion 37 of the contact unit, the pattern of which does not change when the load is varied. With the only really flexible portion of the contact unit always under substantial stress, as will next be described, and so arranged that the flexure pattern therein remains the same whether or not the movable contact is in engagement therewith, it will be seen that a constant damping is applied to the spring and vibration is inhibited, particularly when the circuit is being closed, which is the time of greatest potential difference between the stationary and movable contacts.

By "stress pattern" is meant the disposition of lines and curves of stress in the material of the contact unit such as might be illustrated in a transparent replica under polarized illumination. A change in stress magnitude such as is effected when the preload is transferred to the movable contact only changes the intensity of the stress pattern lines without changing their shapes or positions on the contact unit, hence the "pattern" is the same.

In order that the stationary contact unit may effectively cooperate with the various engaging surfaces of the casing to be held therein without fastening and be properly preloaded, it is essential that it be accurately shaped to conform to the shape of the casing surfaces, which themselves present no difficulty because of the uniformity of results achieved in molding. Metal of spring hardness is difficult to bend to small angles to exact pattern, and for this reason the connecting portion 37 and the blade 41 remain in the same plane as that of the original stock from which the unit is stamped, whereby no inaccuracies occur in their relative dispositions, until the unit is assembled in the casing.

Preloading of the stationary contact units is effected automatically by their mere insertion into the proper places in the casing because of cooperative surfaces on the two parts. To immobilize the terminal portion 35 of each contact unit it has attached thereto by means of terminal screw 50 a rectangular block 51 of rigid metal of substantially the same dimensions as the part 35. The slot permits assembly of these two parts without removing the screw which is threaded into the block. This composite terminal is received in close fitting, facing vertical grooves 52 in the side walls of the casing, as seen in Figs. 2 and 4. The offset portion 36 being narrower than the terminal portion permits the latter to fit in these grooves, as seen in Fig. 1, with the upper edge of the terminal substantially flush with the top of the housing where it will be engaged by the cover 12 and firmly positioned. The slight variation from 90° of the angle between the terminal and offset portions allows the latter to have resilient engagement with the edge 53 (Fig. 4) at the wall extending between the bottoms of the slots to insure against looseness of the terminal in its grooves. The side wall is cut away to permit access to the terminal screw 50 for attaching a conductor thereto.

Fig. 4 shows how the offset portion 36 of one of the stationary contact units rests on the side wall of the casing and holds the connecting por-

tion 37 clear of the casing walls. It also shows at the left, where the contact has been omitted, the notch 55 which forms the fulcrum for the heel of the blade. This notch is formed between two abutments 57 and 57' on the end wall 56 of the casing. The latter abutment is best seen in Fig. 2, and has walls which slope in two directions, thus forming a funnel-like entrance and insuring proper positioning of the heel 46 in the notch 55 when the contact unit is slid into position.

While the heel of the unit is sliding into the previously mentioned funnel-like entrance to the notch 55, the intermediate portion of the inner face of the blade engages the sloping side wall 58 of the yoke stop 25. As it moves down over the wall a portion of the angularity of blade to plane of terminal area 35 is deflected out of it, as seen in Fig. 3, where the dotted lines represent the blade as formed and the solid lines the deflected position of the blade when the contact unit has been fully pressed home into the casing. This figure also shows the flaring of the inner or unused face 60 of the notch 55 to clear the heel of the blade and eliminate any chance of blade bending. It is only the shoulder 61 against which the blade fulcrums, either under the action of the inclined edge 58 of the yoke stop as it is being inserted or when contacted by the yoke. It will be noticed that this inclined edge 58 becomes straight at 63 where the blade comes to rest, in order to engage over most of the vertical width of the same.

As seen in many of the figures, the yoke stops 24 and 25 whose inclined lateral edges provide the movement to preload the contacts, extend up integral from the bottom wall of the casing and are secured to the end walls respectively by webs such as 24', 25', to increase their rigidity.

The switch illustrated is of the single pole, single throw type and connection is made by the yoke bridging the blades to close the circuit. In the event that a double throw switch is desired the contact assembly shown at the right hand end of Fig. 2 is duplicated at the other end of the casing and the added contacts are engaged by the same yoke when in its opposite position. For a three-way switch this same arrangement of duplicate sets of contacts is provided and the contact terminals on one side are connected together by a bridging strap.

When each stationary contact unit is inserted in the casing the lower edge of its terminal area 35 and connected terminal block 51 is first received in the upper ends of the appropriate facing slots 52 prior to engagement of the blade against the corresponding yoke stop. This then insures against any rotation of the terminal area about a vertical axis as the heel of the blade enters the slot 55 and the intermediate portion of the blade engages the sloping surface 58 at the edge of the yoke stop member, deflecting the blade and preloading the connecting portion 37. Thus when the units are pressed home the blades are assured of being properly positioned and spaced to receive the entering portion of the yoke which contacts them.

By carefully determining the relative positions of the slot surface 61 and the sloping edge 58 of the yoke stop, the degree of preload given the contacts is readily controlled. Because of the careful spacing of the terminal receiving slots 52 in respect to the heel slots 55 no bending flexure of the connecting portion 37 of the contact is effected. Substantially all of the preload

is concentrated in the spring-like section 37 in pure torsional stress.

The blades extend for somewhat less than one-half of their length inward beyond the stop 25 to receive the yoke, as shown in Fig. 5. The rigidity of the blades resulting from flanges 41 prevents any substantial flexure thereof so that when the yoke enters between the outer ends of the blades it quickly assumes the load which the stressed contacts placed on the yoke stop by lifting them clear of its edges. When the yoke engages the blades only very little additional stress is given to the sections 37 because of the slight amount of movement of the forward edges of the blades. The yoke is guided by and passes readily between the flared tips 44 of the blades and over the lines of inflection 45 and then allows the blades to close in slightly behind it in a manner somewhat exaggerated in Fig. 5. This insures against any rebound of the yoke when it strikes the stop 25, and also provides for adequate retardation of the yoke until it is snapped free at high acceleration to minimize arcing when the circuit is broken. The slight additional deflection imparted to each blade by the yoke is wholly transferred from the blade to connecting section 37 where it merely increases the torsion in this strip. Thus there is no change in the pattern of the stress in the contact and no tendency toward vibration. The stationary contacts being always under at least a predetermined load are fully damped against the type of vibration resulting from the snap closing of the circuit and thus superior switch action is achieved, which results in extremely long life under the most adverse conditions.

We claim:

1. A switch of the type described having in combination, a pair of terminals, spaced contact units one connected to each terminal, a snap-actuated member having a rigid connector movable into and out of bridging relation with said contact units, a casing supporting and coordinating said parts, each of said contact units including, a mounting portion, a relatively narrow connecting portion, and a rigid foot-like blade at the remote end of the connecting portion, means in said casing engaging each contact unit to immobilize the mounting portion and engage the blade portion on the outside near the connecting portion and on the inside intermediate its length to apply initial torsional stress only, to said connecting portion, said blade portions being arranged side by side with the blades divergent for entrance of said rigid conductor, certain of said means being so related to said blades that the resultant increase in divergence increases the said torsional stresses, said last mentioned means preventing the application of bending stress to said connecting portions.

2. A snap switch of the type described having in combination, at least one pair of symmetrical disposed spaced contact units each including a mounting portion, a relatively narrow resilient connecting portion extending therefrom and a rigid blade projecting laterally from the connecting portion at the free end thereof and having a heel at the rear edge of the connecting portion, a casing receiving said units and immobilizing the mounting portions thereof, fulcrum means in said casing engaging the heel of each blade portion, means normally engaging a side of each blade portion intermediate its ends to impart initial torsional stress to the connecting portion, a rigid conductor arranged in said casing for oscillation from and to a position bridging said blades, said conductor when bridging so engaging the blades as to increase the torsional stress on said connecting portions by moving the blades farther about their fulcrums in the casing.

lation from and to a position bridging said blades, said conductor when bridging so engaging the blades as to increase the torsional stress on said connecting portions by moving the blades farther about their fulcrums in the casing.

3. A snap switch of the type described having in combination, at least one pair of symmetrical disposed spaced contact units each including a mounting portion, a relatively narrow resilient connecting portion extending therefrom and a rigid blade projecting laterally from the connecting portion at the free end thereof and having a heel at the rear edge of the connecting portion, a casing receiving said units and immobilizing the mounting portions thereof with the blades spaced side by side, fulcrum means in said casing engaging the heel of each blade portion, means in said casing fitting between the blades and engaging their sides intermediate the ends to slightly rotate them about their fulcrums and impart initial torsional stress to each connecting portion, a rigid conductor arranged in said casing for oscillation from and to a position between and engaging said blades, said conductor being of such length as to increase the said torsional stress by rotating the blades farther about their fulcrums.

4. The switch as defined in claim 3 in which the means in the casing fitting between the blades and prestressing the connecting portions is a stop for the said conductor.

5. A snap switch of the type described having in combination, a pair of oppositely disposed, sheet metal contact units each including a mounting portion, a relatively narrow resilient connecting portion extending therefrom and a foot-like blade projecting from the free end of the connecting portion, a casing receiving said units, means immobilizing the mounting portions so as to space the blades substantially parallel to each other, fulcrum slots in said casing receiving the heels of the blade portions, means between the blade portions imparting torsional stress to the connecting portions, a rigid conductor mounted for oscillation from and to a position between and engaging said blades beyond said means, said member being of such length as to increase the torsional stress on said connecting portions by moving the blades apart about their fulcrums in the casing, and means to increase the blade rigidity to restrict deflections thereof.

6. The switch as defined in claim 5 in which each contact unit is formed from a sheet of metal, the blade and connecting portion remaining in the same plane of the metal sheet until stressed in the casing.

7. A contact unit for snap switches comprising in combination, a single piece of sheet metal of spring hardness formed to provide a relatively large flat terminal area for immobilization by a switch casing; an offset portion extending laterally of the plane of said area from one edge thereof; a flange extending from the remote edge of the offset portion and oppositely to said area; a narrow connecting portion forming a prolongation of a portion of the width of said flange; a blade in the plane of said flange and connecting portion and extending from a side of the latter; a flange on the longest edge of the blade to stiffen the same; a guide tab at the free end of the blade deviating from the plane thereof and a heel at the opposite end of the blade for cooperation with a suitable fixed fulcrum.

8. The contact unit as defined in claim 7 in which the connected edges of the offset portion are inclined toward each other to direct the

planes of the blade and terminal area toward intersection in a line parallel to the long axis of the connecting portion.

9. A contact unit for snap switches comprising in combination, a single piece of sheet metal of spring hardness formed to provide a terminal area adapted to be immobilized by suitable housing parts; an offset portion extending from and at a substantially right angle to one edge of said area; a narrow connecting portion extending from one edge of the offset portion and in a plane at a large angle to the plane thereof and adapted to be torsionally stressed in use; a blade longer than the width of said portion projecting from one long edge of the connecting portion and adapted to be engaged adjacent its junction with the connecting portion and also intermediate its length by suitable housing parts to stress the connecting portion; said connecting portion and said blade being in the original plane of the sheet metal stock.

10. A snap switch having in combination a housing, a relatively stationary resilient contact, means on said housing to engage said contact in three spaced areas to preload said contact by pure torsional flexing of the same to a predetermined stress pattern, a rigid contact, means to oscillate said rigid contact into such engagement with the first contact as to lift it from one of the engaging areas and assume the load from the preload means, said stationary contact being so mounted as to prevent deflection thereof in the direction of movement of the rigid contact and constructed and arranged as to retain the original stress pattern upon such load assumption.

11. A snap switch of the type described having in combination, at least one pair of symmetrically disposed spaced contact units each including a mounting portion, a relatively narrow resilient connecting portion extending therefrom and a rigid blade projecting laterally from the connecting portion at the free end thereof and having a heel at the rear edge of the connecting portion, a casing receiving said units and immobilizing the mounting portions thereof, fulcrum means in said casing engaging the heel of each blade portion, said blades being so positioned in respect to the mounting portions as to initially toe in, means in the casing between said blades to engage them intermediate their ends to reduce the toe in and impart initial torsional stress to the connecting portions, a rigid conductor arranged in said casing for oscillation from and to a position between and engaging said blades nearer their free ends than said casing means, said conductor being of such length as to increase the torsional stress in said connecting portions but allowing them to close behind it to prevent rebound.

12. A snap switch of the type described having in combination, a pair of oppositely disposed spaced contact units each including a mounting portion, a relatively narrow resilient connecting portion extending therefrom and an elongated rigid blade projecting laterally from the connecting portion at the free edge thereof and having a heel at the rear edge of the connecting portion, an insulating casing supporting said units and having means immobilizing the said mounting portions, a fulcrum in said casing engaging the heel of each blade portion, means on the casing between said blades to engage them intermediate their ends to slightly rotate them apart about their fulcras to impart initial pure torsional stress

to the connecting portions, a rigid conductor arranged for snap oscillation in said casing from and to a position between and engaging the portions of said blades extending beyond said stress imparting means to increase the torsional stress.

13. A switch of the type described having in combination, a pair of terminals, spaced contact units one connected to each terminal, a snap-actuated member having a rigid connector movable into and out of bridging relation with said contact units, a casing supporting and coordinating said parts, each of said contact units including an elongated rigid blade portion, a mounting portion immobilized by the casing and a narrow connecting portion meeting the blade at right angles, means forming a part of said casing engaging each contact unit at longitudinally spaced positions thereon to apply initial torsional stress to said connecting portion, said blade portions being localized by said casing means so as to be each engaged by said bridging connector near one of said casing means to increase said torsional stresses, said casing means and contact units being so constructed and positioned relative to each other as to apply zero bending stresses to the units at all times.

14. A switch of the type described having in combination, a pair of contact units each including a mounting portion, an elongated rigid blade portion and a narrow intermediate connecting portion extending normal to the axis of the blade portion, a casing supporting said units with the blade portions spaced apart and confronting each other, said casing being constructed and arranged to engage and immobilize the said mounting portions and having means to engage each of the blade portions at two axially spaced positions to apply initial pure torsional stress to its connecting portion, and a rigid conductor mounted in said casing for oscillation from and to a position between and bridging said blades, said conductor in bridging the blades so engaging and moving them each from one of said casing engaging means as to increase the torsional stress in the connecting portion thereof.

15. A switch of the type described having in combination, a pair of contact units each including a mounting portion, an intermediate connecting portion extending longitudinally therefrom and an extended rigid blade projecting normal from the end of said portion, a casing supporting said units with the blade portions spaced apart, said casing being constructed and arranged to engage and immobilize the said mounting portions and having means to engage each blade portion on opposite sides to apply initial torsional stress to its connecting portion, and a relatively inelastic conductor mounted for oscillation from and to a position between and bridging said blades, said conductor in bridging the blades so engaging and moving them each about one of the casing means as to increase said initial torsional stress in the connecting portion while maintaining the stress pattern therein unchanged.

16. A snap switch of the type described comprising in combination, a resilient stationary contact unit having a mounting portion, an intermediate flexing portion and a rigid blade portion normal to the flexing portion, a rigid contact oscillatable to and from engagement with the said blade portion, a casing for said unit and contact and arranged to immobilize said unit mounting portion, means in said casing fulcruming one end of said blade, a portion in said casing engaging said blade remote from the ful-

crum to apply a preloading stress of pure torsion to the flexing portion of said unit, said unit, housing and rigid contact being so constructed and related that the blade is lifted from the projection and the preload is assumed by the rigid contact while maintaining the initial stress pattern unchanged in the flexing portion of the unit.
